Primary Examiner — Ricky Pham

(74) Attorney, Agent, or Firm — Banner & Witcoff, Ltd.

(57) **CLAIM**

The ornamental design for a grill with drip tray, as shown and described.

DESCRIPTION

FIG. 1 is a right front perspective view of a grill with drip tray showing our new design;

FIG. 2 is a left front perspective view thereof;

FIG. 3 is a front view thereof;

FIG. 4 is a left side view thereof;

FIG. 5 is a right side view thereof;

FIG. 6 is a right front perspective view of an alternative embodiment of a grill with drip tray showing our new design;

FIG. 7 is a left front perspective view thereof;

FIG. 8 is a front view thereof;

FIG. 9 is a left side view thereof; and,

FIG. 10 is a right side view thereof.

The broken lines depicting the remainder of the grill with drip tray form no part of the claimed design.

1 Claim, 10 Drawing Sheets
